CALCULATING MACHINE

Joseph A. V. Turck, Wilmette, Ill., assignor to
Felt & Tarrant Manufacturing Company, Chi-
cago, Ill., a corporation of Illinois

Original application July 31, 1923, Serial No.
654,874. Divided and this application July 1,
1932, Serial No. 620,505

6 Claims. (Cl. 235—27)

This invention relates in general to improvements in calculating machines and more particularly to improvements in ordinal locking mechanism whereby the ordinal actuating mechanism 5 may be selectively operated by key-drive or key-set power drive. The present application relates especially to the ordinal locking mechanism disclosed in my copending parent application Ser. No. 654,874, filed July 31, 1923, now Patent No. 10 1,869,872, dated August 2, 1932, of which this application is a division.

Briefly stated, the machine of the present invention includes in its construction the following features or any one or combination of them, ordinal column actuating mechanism alternatively operable by ordinal key-drive or by key-set power, in the present instance crank, drive; a manually-controlled device for determining the character of drive of the column actuators; a power 20 mechanism for driving the column actuators in key-set power-driven actuation; ordinal keys for driving the column actuators in key-driven operation or for setting said actuators for power driven actuation.

25 The invention provides the further feature of providing a permanent connection of all of the actuators with the power drive while yet permitting key-driven operation or key-set operation of any selected actuator.

30 In addition to the general objects recited above the invention has for further objects such other improvements or advantages in construction or operation as may be found to obtain in the structures and devices hereinafter described or 35 claimed.

In the accompanying drawings, forming a part 40 of this specification and showing, for purposes of exemplification, a preferred form and manner in which the invention may be embodied and practiced, but without limiting the claimed invention specifically to such illustrative instance or instances:—

Fig. 1 is a top plan view of a part of a calculating machine constructed in accordance with 45 the present invention;

Fig. 2 is a left hand side elevation of the machine showing a part of the side casing plate broken away to illustrate part of the power drive;

Fig. 3 is a vertical section taken longitudinally 50 of the machine and showing the parts of the actuating mechanism in normal position; and

Figs. 4 and 5 are respectively fragmentary perspective, and transverse sectional views showing the column actuator locking mechanism and the 55 control keys whereby the locking mechanism may

be variously released or set. In Fig. 5, the view is towards the front of the machine.

As the present invention may be used with various types of calculating machines, and as the general construction may be readily understood by reference to my copending parent application, Ser. No. 654,874, a brief description of the general features of this machine will be sufficient for an understanding of the present invention. The same reference characters used in 10 said application will be used herein to designate the same parts. Figs. 1 to 5 are identical copies of Figs. 1, 4, 5, 9 and 10, respectively of said application.

The various instrumentalities, which constitute 15 the actuating mechanism from which calculative motion is transmitted to the accumulator mechanism, are supported by a frame mounted on the base 21 of an enclosing casing, said frame consisting essentially of side skeleton plates 22 and 20 intermediate skeleton plates 23 disposed between the various actuating mechanism of the several orders of the machine, and all tied together at suitable points by transverse tie rods 24. The various orders of the actuating mechanism are 25 "stationary", i. e., there is no shift from order to order of the actuating mechanism. In performing multiple-stroke key-set power-driven calculation, shifting is effected by the carriage which supports the accumulator mechanism, as herein- 30 after described.

According to the present type of machine, a number of columns of nine keys each are provided, a column for each order of the machine. Each column of keys 25 corresponds with the 35 column actuator and attendant parts and constitutes a mechanism either for driving the column actuator an amount proportionate to the digital value of the particular key operated or for setting and controlling the column actuator 40 to be otherwise driven a like amount. The keys of each column are numbered from "1" to "9" and complementally for negative calculation from "0" to "8" in front to rear order of the machine; the key at the extreme front is adapted 45 to effect or otherwise to control operation of the column actuator through an arc substantially one-ninth of that produced by the operation of the key at the extreme rear of the machine, and upon depression of intermediately positioned 50 keys, the column actuator is or may be moved through various arcs respectively determined by the digital value of the intermediate keys depressed.

Each key 25 is provided with a stem 26 extend- 55

ing down and bearing upon the corresponding column actuator 27 for the key-driven actuation of the machine. Spring mechanisms 28 similar to those employed in the well-known "Comptometer" are utilized for the purpose of restoring the respective keys 25 to normal independently of the column actuator.

There is a column actuator 27 for each column of nine keys of the machine, and each column actuator is preferably constructed in the form of a bell-crank lever having a long horizontal arm 29, a relatively short depending vertical arm 30, and being pivoted at the junction point of said arms to the framework at the rear of the machine, as shown at 31. The horizontal arm 29 of the column actuator extends forwardly from rear to front of the machine and receives the key-impulse to actuate the accumulator, when the machine is set for key-driven actuation. Pivoted at 32 on a fixed shaft extending through and supported by the framework of the machine is an actuator sector 33 for transmitting the calculative motion of the column actuator to the accumulator. The pivoted sector 33 is provided with a set of gear teeth 34 on its arcuate periphery and said teeth are adapted to mesh with ordinal gears 111 forming part of the ratchet mechanisms. Motion produced by the normal movement of the column actuator is transmitted to the pivoted sector 33 by an abutment 35 at the end of a double-arm lever 35a pivoted on the hub of the sector 33 concentrically with shaft 32 and connected with the column actuator by a link 35b. The abutment 35 is normally held in engagement with the rear radial edge 36 of the sector by a spring 37 connecting the forward radial arm 38 of said sector with said abutment 35. So long as any key 25 is depressed only that amount necessary to effect a movement of the sector 33 corresponding with the digital value of the key, the spring 37, during the downward movement of the column actuator arm 29, will hold the sector 33 against the abutment 35. If, however, the key be depressed beyond such normal movement the sector 33 will be arrested, and will be prevented from moving more than the amount of the digital value of the particular key depressed, by the engagement of the respective digital stop 109, of the stop bar 105 that is connected with said sector, with the particular key depressed, but the spring 37 will permit the abutment 35 to move, with a yielding action, away from the sector 33 as the column actuator arm 29 continues to move downwardly.

In key-driven actuation, the column actuators are restored to normal position, i. e., the horizontal arms 29 of said actuators are lifted, respectively by the key-driven functioning member of the corresponding dual flexible link mechanism.

The universal actuator 39 functions as an abutment for causing the spring-tensioning that effects the return movement of the column actuators in key-driven actuation. It comprises a power-driven oscillatory shaft 40 extending transversely of the main frame. Fixed to said shaft 40 so as to partake of its oscillatory movement are the universal actuator plate members 41 which correspond ordinally with the column actuators 27. It is particularly these plate members 41 which constitute the abutments for the spring tensioning hereinafter referred to.

The dual flexible mechanism of each column actuator and corresponding universal actuator

plate comprises an upper link mechanism 42 and a lower link mechanism 43.

In key-driven operation, on depression of the numeral key 25, the horizontal column actuator arm 29 moves downwardly an amount proportional with the digital value of the key depressed. This movement of the column actuator turns the transmitting gear sector 33 in a counter-clockwise direction the required amount for the incremental accumulative actuation, which occurs on the reverse clockwise rotation of the sector 33. The downward movement of the horizontal column actuator arm 29 causes a rearward movement of the depending column actuator arm 30 and this rearward movement of said arm 30 stretches or tensions the spring 44 to produce power for the return movement of the column actuator, inasmuch as the ram 46 remains stationary. In this manner, the spring 44 of the flexible link mechanism functions as the return spring for the column actuator in key-driven actuation. In all forms of calculative actuation, it is the upward return movement of the transmitting gear or adding sectors 33 that effects the actual transfer of incremental ordinal accumulation to the accumulator mechanism, namely, the adding actuation. This is effected by an ordinal internal ratchet mechanism, operating in like manner to that shown and described in the Comptometer patents hereinbefore mentioned in my parent application.

In key-set power-driven actuation, the depression of any ordinal numeral key merely releases or unlocks the column actuator corresponding to its order for subsequent calculative movement by the power mechanism, the operation of a numeral key being a mere unlocking of an ordinal locking device corresponding to the order in which the key is depressed, as contra-distincted from an actual calculative movement produced by key operation in key-driven actuation of the machine. When the machine is set to operate in key-set power-driven actuation, the column actuators in all orders of the machine are locked against movement by an ordinal locking mechanism and only those column actuators are operated which have been released by a setting of one of the corresponding ordinal keys. The oscillatory movement of the universal actuator plates 41 is employed first to depress and then elevate those column actuators which have been released from the ordinal locking mechanism by previous numeral key setting.

In the present embodiment of the invention, such oscillatory movement of the universal actuator is effected by a crank mechanism, see Figs. 2 and 4. The crank 56 is mounted on the outside of the right-hand vertical casing plate at the end of a power shaft 57 which it rotates. The power shaft 57 extends transversely through the supporting frame of the machine and is provided at its left-hand end, see Fig. 2, with a crank 58 on which is pivoted eccentrically to the axis of shaft 57 the forward end of a pitman 59. The pitman 59 extends rearwardly of the machine and is pivoted at its rear end to an oscillatory arm 60 secured to the left-hand end of the shaft 40. The connections in the above described universal actuator train are so proportioned relatively to each other that each single rotation of the crank 56, in either direction, will impart first a clockwise and next a counter-clockwise movement to the universal actuator shaft 40 and the series of ordinal actuator plates 41. In other words, each single rotation of the crank 56 is accompanied by a

downward and upward oscillation of the universal actuator plates. In key-set actuation, each single oscillation of said plates 41 effects a single incremental accumulative movement of the selected column actuators.

The ordinal locking mechanism for preventing actuation of the column actuators by the universal actuator, in power-driven operation, is shown more particularly in Figs. 4 and 5. Extending transversely of and supported by the framework is a bar 66 which constitutes the support for the ordinal locks 67. These locks 67 are respectively pivotally mounted at 68 on said bar 66 and their upper free ends are provided with locking notches 69 which are projected beneath the horizontal arms 29 of the column actuators to prevent depression thereof, whenever the locks 67 have been shifted pivotally toward the left of the machine, (towards the right as seen in Fig. 5), by setting the machine for power-driven operation. Each ordinal lock 67 is controlled individually by its corresponding ordinal lock control bar 70. These bars 70 extend from front to rear in the various orders of the machine and are loosely supported by front and rear rods 71 and 72, which permit the bars to be swung individually or in unison on axes parallel with their length. Each bar 70 is provided with a depending arm 73 the lower end of which has a pin 74, which works in a slot 74a in the corresponding ordinal column actuator lock. When the lower edges of the respective bars 70 are swung in unison toward the right, in a counter-clockwise direction by the mechanism for setting the machine for power-driven operation, the several locks 67, through the connections 73, will be swung toward the right in a clockwise direction (as viewed in Fig. 5) to move the locking notches 69 into engagement with the column actuator arms 29. For this purpose each control bar 70 is provided with a depending arm 75 (see Fig. 4) provided with a slot 76 that receives the grooved portion 77 of a shift rod 78 extending transversely of the framework. The shift rod 78 is engaged at its left-hand end by the upper end of a rocker arm 79. The lower end of said rocker arm is pivoted at 80 on a transverse supporting bar 81. Projecting rearwardly from the upper end of the rocker arm 79 is a roller 82 which forms the abutment for shifting the rocker arm 79 either toward the right or toward the left of the machine, in response to operation of the control key 83. The control key 83 is designated "key drive" and is provided below the top casing plate with a notch 84 that loosely receives the rear end of a walking beam 85. The center of the walking beam 85 is pivoted at 86 to the side skeleton plate of the framework and the front end of said beam is loosely mounted within a similar notch 87 in the "crank drive" control key 88. The notches 84 and 87 are so located in the respective control keys 83 and 88 that the walking beam 85 will elevate one key as the other is depressed. The "key-drive" control key 83 is provided with an upper notch 89 and a lower notch 90 (Fig. 4) so located that when the "crank drive" control key 88 is depressed the notch 90 is in engagement with the roller 82 on the upper end of the rocker arm 79, and when the "key drive" control key 83 is depressed the upper notch 89 is in engagement with the roller 82. As shown in Fig. 9, the upper notch 89 is located farther toward the right of the machine than the lower notch 90. When the crank drive control key is depressed and the key drive control key is concurrently elevated, the position-

ing of the notch 90 in registry with the roller 82 permits the several control bars to move toward the left of the machine (or toward the right as viewed in Fig. 5) to shift the several ordinal locks 67 into locking positions. This movement of the control bars 70 is accomplished by springs 91 encircling the supporting rods 71 and 72 in the various orders of the machine between each control bar and the corresponding ordinal skeleton plate and bearing on the control bars in such manner as to push their depending arms 73 toward the left of the machine, i. e. toward the righthand side of Fig. 5, to effect the movement of the several ordinal locks 67 into column actuator locking positions. On the other hand when the "key drive" key 83 is depressed the upper notch 89 is brought into registry with the roller 82, and such movement of the key 83 causes the rocker arm 79 to move toward the right of the machine, with the result that the rod 78 is likewise moved toward the right. This movement of the rod 78 is transmitted to the several control bars 70 in unison through the arms 75, thereby shifting the connecting arms 73 in unison toward the right of the machine (i. e., toward the left-hand of Fig. 5) to shift all the ordinal locks 67 into inoperative positions. The last described operation effected by depression of the key 83 sets the machine for key-driven actuation, whereas the depression of the key 88 sets the machine for power-driven actuation.

As hereinbefore stated, when the machine is set for power-driven actuation, the depression of an ordinal numeral key 25 unlocks the ordinal lock 67 of the corresponding order. For this purpose each control bar 70 is provided with a series constituted of nine depending projections 92 which respectively correspond to the column of nine numeral keys 25 of the corresponding order of the machine. Each numeral key 25 is provided with a projection 93 located on the right-hand side of its stem 26 and having a notch 94 which receives the corresponding projection 92 of the ordinal lock control bar when the key is in normal elevated position. On depression of the key for key-set actuation the shoulder above the notch 94 engages the control bar projection 92, so that the downward movement of the key causes the lower edge of the control bar to move toward the right of the machine, with the result that the depending connection 73 is also shifted toward the right of the machine (toward the left as viewed in Fig. 5) to throw the ordinal lock 67 of the order corresponding with the key to inoperative position, thereby permitting the universal actuator to effect a calculative movement of the column actuator corresponding with that order. As the key 25 moves downwardly the shoulder above the notch 94 is positioned beneath the projection 92, as shown in Fig. 5, thereby holding the key depressed in key-set position until released either by the universal release mechanism, or as hereinafter described. After the keys of the various selected orders have been "set" as above described, the universal actuator mechanism may be operated either for a single actuation, as in additive calculation, or for as many repeated actuations as desired, when performing multiple stroke calculation.

When the desired calculative actuation has been completed, whether additive or multiple stroke, the several selected numeral keys 25 which have been set are restored to normal positions and the released column actuator locks of their respective orders are re-positioned for locking.

the column actuators. This is accomplished by the universal lock release mechanism, or by changing to key-drive. Pivotally mounted on the transverse supporting bar 81 at the right-hand side of the machine is a rocker arm 95 the upper end of which is slotted to receive one of the grooves of the column actuator lock shift rod 78. A roller 96 projects rearwardly from said rocker arm 95 and normally enters a notch 97 in the "clear" key 98, with the result that the parts remain in normal, or key-set, positions. When the key 98 is depressed, its stem above the notch 97 forces the roller 96 and the upper end of the rocker arm 95 toward the right of the machine, so that the shift rod 78 is likewise moved toward the right, thereby, through the arms 75, shifting the connections 73 toward the right (toward the left as viewed in Fig. 5) to move all the locks 67 to their extreme releasing positions and the projections 92 away from the numeral keys which they have been holding down so that any set numeral keys are permitted to rise under the action of their springs to normal positions. When the "clear" key 98 is released its spring return mechanism, corresponding to the spring return mechanism 28 of the numeral key, will restore it to normal position to reengage the notch 97 with the roller 96. This permits the springs 91 to throw all of the control bars 70 and their corresponding column actuator locks 67 back to locking positions. If desired, however, a resetting may be effected in the same columns that had a previous setting, by merely depressing the numeral keys representing the digits of the new setting, or where a cipher is desired, by operating the columnar release as hereinafter explained. The depression of a key releases any other key set in the same order.

There is also provided a columnar release mechanism employed for the individual column actuator locks 67, for example when it is desired to release either the column actuator lock of any selected column or to move the control bar 70 to its extreme releasing position, to release a numeral key 25 which has been previously "set" in that column. This columnar release mechanism may be employed for correcting an error in the key setting of any column, and permits a new key setting to be made in any column, or for striking a cipher in any column, if a key has been previously set in that column without making it necessary to release the key setting in other columns, as would happen in an operation of the "clear" key 98. Referring especially to Fig. 4, each control bar 70 is provided at its extreme front end with a horizontal shoulder 99 on which rests the lower end of the key stem 100 of the small columnar release or "cipher" key 101. When said key 101 is depressed, the shoulder 99 is moved downwardly to force the lower edge of the lock bar 70 toward the right of the machine, to release a numeral key 25 the shoulder of which is retained beneath a projection 92 of said control bar. Inasmuch as there are release or "cipher" keys 101 for each column, the setting of any individual column is subject to individual control and to resetting in any manner desired by the operator. When the finger is removed from a depressed key 101 the parts will be restored to normal position by the springs 91 corresponding to the control bar 70 which has been shifted by said key 101 to releasing position.

The setting of the machine for power-driven actuation unlocks the crank 56 for the operation of the universal actuator. When the "crank

drive" key 88 is depressed, the movement of the shift rod 78 toward the right of the machine withdraws the left-hand end 102 of said rod from locking position in a hole or socket 103 in the disk 61 of the main power or crank shaft 57, thus freeing the shaft 57 and crank 58 for movement. This construction also prevents setting of the machine from power-driven to key-driven actuation, except when crank 58 and disk 61 are in their normal positions, since the movement of the disk away from normal also moves the hole 103 out of registry with the shift bar 78 and the latter can not be operated by the "key-drive" key 83 to release the column locks for key-driven operation of the actuating mechanism. When the disk 61 is in normal position, the crank 58 and shaft 57 will be locked against operation by the setting of the machine for key-drive, since the end 102 of the shift bar enters the hole 103 to prevent rotation of the disk 61.

As hereinbefore stated, each complete rotation of the crank 56 produces first a clockwise movement and next a counter-clockwise movement of the shaft 40 and ordinal universal actuator plates 41. Those column actuators which have not been set for power-driven operation are locked against movement by their corresponding column locks 67, but, in the various orders in which key-setting has taken place, the respective column actuator arms 29 may move variably downwardly, in accordance with the digital value of their respective key-settings, until their motion is arrested by the digital control device hereinafter explained. The dual flexible link mechanism connecting the universal actuator plates 38 with the column actuators in the several orders, permits the constant oscillatory motion of the plates 41 in all orders, although column actuators have been set for relatively variable movements and in some orders, as required by the example to be performed, no setting of the column actuators may have taken place at all.

This operation is as follows: On the clockwise movement of a universal actuator plate 41, the upper flexible link mechanism 42 pulls down with said plate 41 the horizontal arm 29 of the corresponding column actuator, if said actuator has been previously set by the depression of a numeral key 25. There is no stretching or tensioning of the spring 50 so long as the arm 29 is moving downwardly, and, inasmuch as the stud 49 is traveling in the slot 48 of the ram of the lower flexible link mechanism 43, there is likewise no stretching or tensioning of the spring 44. When, however, the downward movement of the column actuator arm 29 has been completed to effect the required incremental accumulation and said column actuator arm has been arrested by the digital stop device, the spring 50 will be stretched or tensioned proportionally with the remainder of the clockwise stroke of the universal actuator plate 41. During the counter-clockwise return stroke of the universal actuator plate 41, the stud 49 travels freely in reverse direction in the slotted head of the ram 43 without tensioning the spring 44, and the pull on the spring 50 of the upper flexible link mechanism being released, the spring 50 retracts to lift up its ram 52 and also to restore the horizontal column actuator arm 29 to its normal elevated position.

If there has been no key-setting of a column actuator in any order of the machine, the horizontal arm 29 is held against movement by its corresponding column lock 67, and the tensioning of the spring 50 of the corresponding flexible

Link mechanism will commence at the beginning of the clockwise stroke of the universal actuator plate 41, and the return movement of said plate 41 allow the tensioned spring to pull back its ram 52 into normal elevated position.

Pivotedly mounted at 104 on the forward arm 38 of the adding sector of each column actuator is a digital stop bar 105 which extends to the front of the machine and has its front end pivoted at 106 to the top of a rocker arm 107, the latter being pivoted on a cross-rod 108. The said bar 105 is provided with a series of eight stops or projections 109 respectively corresponding to the column of digital or numeral keys of its corresponding order, with the exception of the nine key and adapted to arrest the rearward movement of said bar 105 by the depression or setting of a key 25, (see Figs. 3 and 5). The nine key and the movement of the sector 33 corresponding thereto represents the extreme movement of said sector, and such movement is preferably arrested by a fixed stop 109a attached to the framework, although, if desired, a further stop 109 for the nine key could be provided on the stop bar. The stops or projections 109 are located at different distances in front of the keys with which they respectively co-operate, the stop 109 corresponding to the "1" key being the nearest to said key and the stop corresponding to the "9" key being the farthest away. When a key 25 is actuated in key-driven actuation or set for power-driven actuation, the adding sector 33 of the corresponding column may move downwardly until the bar 105 has shifted the corresponding stop 35 into engagement with the key depressed, whereupon the movement of the sector 33 is arrested.

The motion of the adding sectors 33 of the column actuators is transmitted to the accumulator mechanism by ordinal internal ratchet mechanisms, which operate on the same principle as the internal ratchet mechanisms of the standard "Comptometer" type exemplified in the prior patents hereinbefore mentioned in my parent application, for permitting the numeral wheel and transmitting gearing of the accumulator mechanism to remain idle during the rearward down-stroke of the corresponding adding sector 33, but to be actuated to effect the accumulation during the return stroke of said sector. For more complete description of the construction and operation of such mechanism reference is made to my parent application aforesaid.

The invention as hereinabove set forth may be variously embodied within the scope of the claims hereinafter made.

I claim:

1. In a calculating machine, in combination: ordinal column actuators operable for both key-driven and key-set operation; ordinal latches 60 for respectively preventing actuation of the col-

umn actuators; ordinal keys for driving and for setting the actuators and which when operated during key-set operation release the latch in the corresponding order; and a manual control for concurrently throwing all said latches out of 5 operation for key-driven operation.

2. The combination, in a calculating machine alternatively operable for key-driven actuation or key-set power-driven actuation, of a keyboard having keys operable for either mode of 10 actuation, latch mechanism controlling the calculating operation in key-set power-driven actuation, and means, operable at will, for throwing such latch mechanism into or out of operation. 15

3. The combination, in a calculating machine alternatively operable for key-driven actuation or key-set universally driven actuation, of a keyboard having keys operable for either mode of actuation, latch mechanism controlling the calculating operation in key-set universally-driven actuation, and means, operable at will, for maintaining said latch mechanism out of 20 operation during key-driven actuation.

4. The combination, in a calculating machine alternatively operable for key-driven actuation or key-set power-driven actuation, of amount keys operable for both modes of actuation, means for latching down the amount keys during key-set operation, and means, controlled by 25 a depressible key, for throwing the latter means into and out of operation to condition the amount keys for either mode of actuation. 30

5. The combination, in a unitary key-driven 35 and alternatively key-set power-driven calculator, of keys alternatively operable for either type of actuation, means, operable at will, for setting the machine for key-set actuation, ordinal column actuators co-operating with said keys, and locking devices controlled by said setting means for locking all the column actuators against calculative motion, and controlled individually by the keys for releasing column actuators in the orders determined by the key-setting. 40

6. In a combined key-driven and alternatively universally-driven calculating machine, in combination: ordinal amount keys; ordinal differentially movable actuating mechanism alternatively operable by key-driven or by key-set 50 universally driven actuation for effectuating the digital degree of incremental accumulative movement of an accumulator determined by the amount-keys; and ordinal locking mechanism 55 for locking the differentially movable actuating mechanism in each order against universal actuation until a key has been set in said order.

JOSEPH A. V. TURCK. 60
